CAR CONSTRUCTION

Sigvard Simonson, Butler, Pa., assignor to O. C. Duryea Corporation, Wilmington, Del., a corporation of Delaware

Application September 22, 1941, Serial No. 411,926

3 Claims. (Cl. 213—10)

This invention relates to railway car underframes of the Duryea type which provide long travel for resisting draft and buffing shocks with low forces, together with train slack predetermined independently of and preferably shorter than said long travel.

In a form well known in practice the Duryea underframe comprises a draft and buffing column extending substantially the length of the car body and longitudinally movable relative thereto, and car couplers which are suitably mounted at the ends of the column for movement of limited extent relative thereto. The car body is cushioned against draft and buffing shocks by suitable cushion gears interposed between it and the column, these gears comprising various types of spring and friction devices and having relatively long travel to provide low forces. On the other hand, the movement of the couplers relative to the column is also cushioned by suitable coupler cushioning means. For example, in some underframe constructions, which are typified by the patent to Otho C. Duryea No. 1,693,194, coupler cushion springs separate from the long travel cushion gears are used. In other constructions, typified by the patent to Otho C. Duryea No. 1,904,294, the long travel cushion gear springs are disposed between the bolsters and the couplers and are arranged so that their initial compression cushions the limited movement of the couplers relative to the column and their further compression cushions the greater movement of the column relative to the car body.

In practice the draft and buffing column is usually made up of spaced parallel members, such as channels or Z-sections, which are suitably connected together as by cover plates, riveting or welding, etc. Hence it is desirable that the cushion springs in underframes of either type referred to above should be disposed and supported within the column as shown in the aforesaid patents, and the present invention is directed particularly to means for accomplishing this end.

One of the objects of the invention is to provide novel means for supporting and housing a spring within a draft and buffing column of the above type, which means are simple and inexpensive and easy to install but at the same time strong, rugged and durable under practical service conditions.

Another object of the invention is to provide such housing and supporting means in a form which can be readily installed after the draft and buffing column has been completely assembled.

One embodiment of the invention has been illustrated in the accompanying drawings, which show by way of example one end of a Duryea underframe of the type of Patent No. 1,904,294, but it is to be expressly understood that said

drawings are for purposes of illustration only and are not to be taken as a definition of the limits of the invention, reference being had to the appended claims for this purpose.

In the drawings,

Fig. 1 is a side view of one end of an underframe embodying the invention;

Fig. 2 is a plan view in section on the line 2—2 of Fig. 1;

Fig. 3 is a side view in section on the line 3—3 of Fig. 2;

Fig. 4 is a section on the line 4—4 of Fig. 1;

Fig. 5 is a sectional view illustrating diagrammatically the method of installation of the spring housing means in the draft and buffing column; and

Fig. 6 is a sectional view of another construction embodying the invention.

In the particular underframe construction shown herein for purposes of illustration, the draft and buffing column comprises a pair of Z-sections 10 having their lower flanges 11 turned outwardly and their upper flanges 12 turned inwardly and welded together along the line 13. As explained above, the column 10 is movable longitudinally relative to the car body, the floor 14 and end sill 15 of which are shown, and the bars 16 along the upper edges of the column cooperate with hangers 17 secured to the end sill 15 and form part of the means for guiding and supporting the column. A suitable coupler 18 extends inwardly between the members 10 and is connected to the column by a key 19 extending through a slot in the coupler shank and through aligned openings in the members 10 which are defined by ribs 20. The key 19 is retained in position by an enlarged head 21 at one end and a pin 22 at the other end.

In the form shown, the connection between the coupler and the column provides for movement of the coupler relative to the column in the inward direction only. To this end the slot in the coupler shank is longer than the width of the key 19 as indicated by the space 23, and the openings in the members 10 are longer than the width of the key as indicated by the spaces 24. With the parts normally maintained in the position shown in the drawings, the coupler, key and column all move outwardly as a unit on draft without train slack. On buff, however, the coupler can move inwardly relative to the key due to the space 23, and the coupler and key can move inwardly together relative to the column due to the spaces 24, to provide train slack. Such inward movement of the coupler relative to the column moves the follower plate 25 and compresses the coil spring 26, the extent of such relative coupler movement being determined by the space 27 between the follower plate 25 and the outer end of the spring housing means hereinafter described.

Further inward movement of the coupler causes inward movement of the column relative to the car body which is cushioned by further compression of the spring 26, and any suitable means may be provided whereby outward movement of the column compresses the spring 26 against the head 28 of the spring link 29. The operation of such underframes will be clear from the patents referred to above, as well as from other patents such as to the patent to Otho C. Duryea, No. 2,238,163, and from the copending application of William A. Bierman and Sigvard Simonson, Serial No. 400,466, filed June 30, 1941. It will be understood that the particular underframe construction and operation described above is merely for purposes of illustration. Thus while the spring 26 has the dual function of cushioning the movement of the coupler relative to the column as well as the movement of the column relative to the car body, the spring housing means now to be described may be used in any of the underframes referred to above, wherever suitable.

In the form shown in Figs. 1 to 5, inclusive, said housing means comprises two similar but oppositely disposed housing members 30, the cross sectional shape of which is shown clearly in Fig. 4. These housing members may have any suitable length, depending upon the length of spring to be supported, and their central portions are dished or curved in roughly semicircular shape so that when oppositely disposed, they cooperate to form a substantially circular spring housing as shown in Fig. 4. At the edges of the curved portions are marginal flanges 31 which extend laterally through slots in the vertical webs of the members 10 and are suitably secured therein as by welding.

A convenient method of installing the spring housing, after the draft and buffering column has been completely assembled, is illustrated diagrammatically in Fig. 5. It will be observed that the width of the slots in the members 10 is twice the thickness of the flanges 31 so that when juxtaposed, said flanges fit closely in and substantially completely fill the slots. The widths of the curved portions and of the flanges are so proportioned to the width of the draft and buffering column, however, that when the upper housing member is disposed at an angle as indicated in dotted lines at 32, its left-hand flange 31 can be inserted in the slot in the left-hand side wall 10 and the right-hand flange 31 will then swing upwardly inside the right-hand side wall 10 to the position shown in cross section. The right-hand flange 31 of the lower housing member 30 may then be similarly inserted in the slot in the right-hand side wall 10, as indicated by the dotted line position 33, so that the left-hand flange 31 will then swing upwardly inside the left-hand side wall 10 to the position shown in cross section. When this has been done, the upper housing member is moved to the right and the lower housing member to the left until they are centered in the column with both flanges engaged in their respective slots as shown in Fig. 4.

In the form shown in Fig. 6, the upper and lower housing members 34 are curved similarly to the housing members 30 and similarly cooperate to form a substantially circular spring housing. These housing members are provided with

5 marginal flanges 35 which, instead of fitting in slots in the side walls 10, extend only to and engage the inner surfaces of said side walls so that the housing members can be slipped upwardly between the side walls into the desired position and then suitably secured to the side walls as by welding. Preferably said flanges are provided with vertical extensions 36 along their outer edges which engage the inner surfaces of the side walls and provide greater area for welding along the lines 37.

15 It will thus be observed that a simple and inexpensive means is provided for housing and supporting a spring between the spaced vertical side walls of the draft and buffering column. The housing means can be easily installed and constitutes a strong, rugged construction which will withstand the forces encountered under service conditions and operate reliably for long periods. At the same time it can be readily installed after the draft and buffering column has been completely assembled.

20 While two embodiments of the invention have been described and illustrated in the drawings, it is to be expressly understood that these embodiments are for purposes of illustration only and that various changes may be made in the design, details of construction and arrangement of the parts without departing from the spirit of the invention. Reference should therefore be had to the appended claims for a definition of the limits of the invention.

What is claimed is:

1. In a railway car underframe, a draft and 25 buffering column having spaced, vertical side walls, and spring supporting means comprising housing members having oppositely disposed curved portions cooperating to form a spring housing and marginal flanges extending laterally through and secured in slots in said side walls, each of said members being dimensioned so that one flange will be inserted in its slot in one side wall with the edge of the opposite flange lying within the opposite side wall.

30 40 45 50 55 2. In a railway car underframe, a draft and buffering column having spaced, vertical side walls, and spring supporting means comprising housing members having oppositely disposed curved portions cooperating to form a spring housing and marginal flanges extending laterally through and secured in slots in said side walls, the width of said curved portions and flanges being proportioned to the width of said column so that when one flange is inserted in the slot in one side wall the outer edge of the other flange may be swung upwardly inside the other side wall.

60 65 70 3. In a railway car underframe, a draft and buffering column having spaced, vertical side walls, each of said side walls having a slot therein, and spring supporting means comprising housing members having oppositely disposed curved portions co-operating to form a spring housing and marginal flanges extending laterally therefrom, the adjacent flanges on each side of said members both extending through and being secured in the slot in the adjacent side wall, each of said members being dimensioned so that one flange may be inserted in its slot in one side wall with the edge of the opposite flange lying within the opposite side wall.

SIGVARD SIMONSON.
